CERTIFICATE HOLDER

Hanson H. Dedmon, Oakland, Calif.

Application August 12, 1939, Serial No. 289,794

3 Claims. (Cl. 40—19)

This invention relates to certificate holders, and has for its principal objects, an economically manufactured, simple enclosed holder for certificates, such as automobile registration certificates, etc., and which holder is readily opened for insertion or withdrawal of a certificate therefrom, and as readily closed, and when so closed with the certificate therein, is firmly held closed. Another object is a neat, light weight, rugged holder with no metallic parts that may rattle or become loosened, and which holder is also conveniently formed for displaying the desired data thereon without manipulation of the holder. Other objects and advantages will appear in the specification, claims and drawing.

In the drawing,

Fig. 1 is a plan view of the holder.

Fig. 2 is an end elevational view of the holder supported from a supporting member, the latter being indicated in section.

Fig. 3 is an enlarged sectional view taken along line 3—3 of Fig. 1.

Fig. 4 is a modified elevational view of a modified form of cap.

In detail, the holder illustrated in the drawing comprises a pair of caps 1 disposed in opposed relation, said caps having flanges 2 extending towards each other, and a relatively light, flat, spring steel strip 3 extends between said caps, connecting them together and supporting them in opposed relation. The ends of the spring 3 are riveted, soldered, welded, or otherwise rigidly secured to the flange 2 of each cap and said ends may be positioned on the inside of the flanges or on their outer sides, but it is preferable that they be on the inner sides of the caps since in this position their outer edges will squarely abut the inner sides of the caps and will thus provide a more secure connection for resisting any tendency of the caps to become loosened by reason of abnormal abuse.

Secured to said strip 3 at a point centrally between the caps, is a bracket 4, which bracket may be of any desired type, the one illustrated being formed with a spring clamp 5 for clamping to any suitably formed portion 9 of the instrument board or dash of an automobile.

Referring to Fig. 1, it will be seen that the strip 3 may be readily bowed, as indicated at 3' in dotted line, thus carrying the caps to a divergently extending position from their sides to which the strip 3 is connected. When in this position, a transparent, flexible tube 6, as of Celuloid, with the certificate 7 therein (Fig. 3) may quickly be slipped between the caps, and upon

releasing the tension on spring 3, the caps will return to their opposed relation, supporting the tube 6 and the certificate, between said caps with the flanges 2 enclosing the margins of the tube at its opposite ends. To remove the tube 6 and the certificate, caps are merely forced outwardly to bow the spring as indicated at 3' and the tube will fall free from the caps or can be easily removed.

While it is not absolutely essential, it is preferable to make the caps 1 of elliptical shape, since this forms a more compact holder and one in which more room is provided on the side for reading the most important portion of the certificate.

The caps 1 are shown as being imperforate, although one or both may be cut out centrally, as indicated at 8 in Fig. 4. However, the caps are preferably imperforate, to protect the certificate, and the means for securing the caps to each other and the bracket, preferably, do not project beyond the oppositely outwardly facing sides of the cap.

Having described my invention, I claim:

1. A certificate holder comprising an elongated, transparent tube, a pair of opposed closures extending over the opposite ends of said tube, flanges on the said closures extending toward each other and over the margins of the tube at its opposite end edges, a straight strip of spring metal secured at its opposite ends to the flanges of said closures and disposed relatively close alongside said tube, said strip being adapted to be readily bowed centrally of the length of said strip and at that portion thereof that is centrally between the ends of said tube for moving said closures and flanges apart to position out of engagement with the said opposite ends of the tube for freeing said tube, said strip and flanges being rigidly secured together against movement of the flanges and closures relative to the strip.

2. A certificate holder comprising an elongated transparent tube, a pair of opposed closures extending over the opposite ends of said tube, flanges on the said closures extending toward each other and over the margins of the tube at its opposite ends, a straight strip of spring metal secured at its opposite ends to the flanges of said closures, said strip being adapted to be readily bowed for moving said closures and flanges apart to position out of engagement with the said opposite ends of the tube for freeing said tube, said strip and flanges being rigidly secured together against movement of the flanges and closure relative thereto, the ends of said strip

being secured to the inner sides of the flanges on said closures whereby the said tube is directly supported against the strip throughout its length.

3. A certificate holder comprising an elongated, open-ended, tube of transparent, flexible material, a cap removably fitted over each of the open ends of said tube, means supporting said caps with said ends of the tube so fitted thereon for movement of said caps in arcuate paths away from said ends to release said tube, said means comprising a straight strip of resilient spring

metal rigidly secured at its ends directly to said caps and being readily bowable longitudinally thereof by flexing of said strip manually centrally of its ends to thereby effect said movement, means supporting said strip in a manner to enable such flexing thereof, said last mentioned means comprising a bracket projecting from said strip and secured thereto at a point intermediate the ends of said strip. 5
